Primary Examiner—Raphael Barkai

(74) Attorney, Agent, or Firm—Nixon & Vanderhye, P.C.

(57) CLAIM

The ornamental design for a "television set," as shown and described.

DESCRIPTION

FIG. 1 is a perspective view of a television set in accordance with my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevational view thereof; and,

FIG. 7 is a left side elevational view thereof.
